UNITED STATES PATENT OFFICE.

JOSEPH SHAW GAUNT, OF MANCHESTER, AND HARRY DYSON, OF HUDDERSFIELD, ENGLAND.

SPINDLE MECHANISM OF SPINNING AND LIKE FRAMES.

Application filed October 8, 1921. Serial No. 506,423.

To all whom it may concern:

Be it known that we, JOSEPH SHAW GAUNT, resident of Manchester, in the county of Lancaster, England, and HARRY DYSON, resident of Huddersfield, England, both subjects of the King of Great Britain, have invented certain new and useful Improvements Connected with the Spindle Mechanism of Spinning and like Frames, of which the following is a specification.

This invention relates to improvements in continuous spinning and doubling machines, and the chief object is to provide an improved method of mounting the spindle whereby the latter shall turn freely under the tension of the yarn or thread in order to impart the requisite twist to the latter and this when the nose of a cop is being wound near the top of a spindle; a further advantage of the improved construction is that when a cop of increased length is to be wound it is necessary for the spindle to be increased in length to an extent that corresponds directly with the increase in the length of the cop, whereas in those of previous constructions where the spindle bolster bearing was mounted on the fixed rail, the increase in length of the spindle had to be twice the increase in length of the cop.

According to this invention the spindle is mounted in a single upper bearing which may be a plain bearing and a footstep, both carried by a bolster mounted upon the lifting rail; the said upper bearing may be secured to the bolster in any convenient way—for example, by frictional engagement—and the bolster may be cut away, giving access to the spindle and enabling drag to be applied; and the footstep may comprise a ring, which may be capable of slight lateral movement with a recess in its underside to receive a disc having a central hollow or recess to receive the lower end of the spindle—as has already been proposed—the said disc is, however, in the present case, permitted a slight radial movement in the recess in the ring and the latter may be held in position by a helical spring arranged within the bolster and may have for its upper abutment the upper bearing or other fixed part adjacent thereto.

Below the upper bearing and integral therewith a stop ring may be formed; this ring may be adapted to act as the upper abutment for the helical spring, as described

above, and may also be adapted, during doffing, to engage—as is well understood—with a flange projection or collar formed or provided near the lower end of the spindle to prevent the latter from being withdrawn from its upper bearing. The space between the upper bearing proper and the stop ring may coincide with a space in the bolster made by cutting away the latter to give access to the spindle in order to apply the drag; and behind the spindle diametrically opposite the point of application of the drag, a support, consisting of a downward extension of a portion of the bearing may be provided for the spindle.

The drag levers or frames may be mounted upon pivots fitting into recesses formed in the lower portion of the bolster.

In the accompanying drawings—

Figure 1 is an elevation of one construction of spindle apparatus according to this invention, and

Figure 2 is a vertical section of the same; Figure 3 is an elevation of a modified construction, also according to this invention.

Figure 4 is a view of a detail; and

Figure 5 is a sectional elevation showing a further modification.

A is a spindle, B a spindle bolster, C a lifting rail, D a flyer, and E a fixed rail.

The bolster B is mounted upon the lifting rail C; and the spindle A is mounted in the said bolster by means of an upper bearing G (shown in elevation and plan in Figure 4) through which the spindle A passes and rests with its lower end in a footstep bearing consisting of a ring F and a disc f. The bolster B consists of a tubular upper portion with a flange B¹ at its lower end and a downward projection B²; the flange B¹ rests upon the lifting rail C and the projection B² extends through a corresponding hole bored in the said lifting rail the lower faces of the latter and of the projections B² lying flush, as shown. In the construction shown in Figures 1 and 3 the projection is formed with a tapped hole b² enabling the bolster B to be firmly secured to the lifting rail C by means of a washer and stud B³; whereas in the construction shown in Figure 3 the projection B² is formed with an external thread upon which is screwed a nut B⁴. J is a frame or lever mounted upon the bolster B by means of pivots J¹ engag-

100
105
110

ing with holes B^5 formed diametrically opposite each other near the lower end of the bolster; upon the end j of one arm of the frame J there is arranged a drag member j^1 , whilst the end j^2 of the other arm of the frame carries the usual drag weights. The upper portion of the bolster is cut away at b to afford the member j^1 access to the spindle.

10 The portion of the spindle that runs within the bolster is of uniform thickness and is provided with a flange A^1 near its lower end; and the portion of the spindle without the said bolster tapers slightly and uniformly towards its upper end. The apparatus is shown so proportioned that approximately one third of the spindle is contained or enclosed within the bolster leaving the upper two thirds exposed: we have obtained satisfactory results with apparatus thus constructed, but we do not wish our invention to be limited to such proportions.

15 The bearing member G comprises at its upper portion, a plain bearing G^1 for the spindle A ; at its lower portion, an abutment or stop G^2 , against which, during doffing, the flange A^1 of the spindle A will come into contact thus preventing the latter from being withdrawn from the bolster B ; and between the bearing G^1 and the stop G^2 the member is cut away, as at G^3 , to expose the spindle to the drag member j^1 the remaining connecting portion G^4 acting as a support for the spindle in opposition to the action of the drag. The said bearing member G engages frictionally within the upper end of the bore of the bolster, and it is provided with a flange G^5 that rests upon the upper edges of the bolster B as shown in Figure 2.

20 The footstep bearing ring F has a very slight lateral play within the bore of the bolster B ; and is formed with a circular recess F^1 in its underside and within this recess the disc F is arranged, the latter also having a slight lateral play within the recess F^1 and being formed with a central hollow or recess f^1 in its upper face for the pointed lower end of the spindle A . Movement of the ring F is restrained by a helical spring F^2 arranged within the bolster B and having its upper end abutting against the stop G^2 of the bearing member G .

25 In the construction shown in Figure 2 the footstep bearing F is shown resting upon the bottom of the bored hole in the bolster. In Figure 5, however, the bolster is shown bored straight through; the lower end is tapped as at b^1 ; and a screwed plug B^5 is provided to support the footstep bearing F . It will be noted that in this construction the bolster B is secured to the rail C in the manner already described with reference to Figure 3.

30 65 The improved construction of spindle

mounting on the lifting rail, as described above, enables us considerably to simplify the construction of the said cup or flyer mounted upon the fixed rail. In the drawing two forms are shown each consisting of a cup d^1 and a whorl d^2 mounted by means of ball bearings in the known manner, but merely provided with a supporting ring d^3 secured to the fixed rail, all spindle bearings being dispensed with: it therefore follows that to increase the length of the cop it is only necessary to increase the length of the spindle by an amount equal to the increase in the length of the cop.

35 With heavy spindles such as are used for spinning coarse numbers it may be advantageous to make the flange A^1 removable, and it may be fixed upon the spindle after the lower portion of the latter has been passed through the bolster bearing.

Having described our invention, what we claim and desire to secure by Letters Patent is:—

1. In a continuous spinning and doubling machine the combination of a lifting rail; a bolster mounted upon the said rail; a bearing arranged in the upper portion of the said bolster, the wall of the said bolster and a portion of the bearing being cut away to expose the spindle and enable the drag to be applied; a footstep arranged in the lower portion of the bolster; and a spindle mounted in the said upper and footstep bearings.

2. In a continuous spinning and doubling machine the combination of a lifting rail; a bolster mounted upon the said rail; a plain bearing comprising an upper bearing portion and a lower abutment portion adapted to engage within the upper portion of the bolster, the wall of the bolster and a portion of the bearing being cut away to expose the spindle and enable the drag to be applied; a footstep arranged in the lower portion of the bolster; and a spindle mounted in the said upper and footstep bearings.

3. In a continuous spinning and doubling machine the combination of a lifting rail; a bolster mounted upon the said rail; a plain bearing comprising an upper bearing portion, a lower abutment portion, and an intermediate supporting portion forming a downward continuation of a segment of the upper bearing portion the said plain bearing being adapted to engage within the upper portion of the bolster, the wall of the latter and a coincident portion of the bearing opposite the intermediate supporting portion thereof being cut away to expose the spindle; means for applying drag to the exposed portion of the spindle; a footstep arranged in the lower portion of the bolster; and a spindle mounted in the said upper and footstep bearings.

4. In a continuous spinning and doubling machine the combination of a lifting rail;

a bolster mounted upon the said rail; a bearing arranged in the upper portion of the said bolster; a footstep arranged in the lower portion thereof and comprising a 5 ring having a central perforation for a spindle and a circular recess in its under side, a disc arranged in the said recess; resilient means for holding the ring and disc of the footstep in position; and a spindle 10 mounted in the said upper and footstep bearings.

5. In a continuous spinning and doubling machine the combination of a lifting rail; a bolster mounted upon the said rail; a plain bearing comprising an upper bearing portion, a lower abutment portion, and an intermediate supporting portion forming a downward continuation of a segment of the upper bearing portion the said plain bearing being 15 adapted to engage within the upper portion of the bolster, the wall of the latter and a coincident portion of the bearing opposite the intermediate supporting portion thereof being cut away to expose the spindle; means 20 for applying drag to the exposed portion of the spindle; a footstep bearing arranged in the lower portion of the bolster and comprising a ring having a central perforation for a spindle and a circular recess in its under side, and a disc arranged in the said recess; 25 resilient means for holding the ring and disc of the footstep in position; and a spindle mounted in the said upper and footstep bearings.

6. In a continuous spinning and doubling machine the combination of a lifting rail; a bolster mounted upon the said rail; a bearing arranged in the upper portion of the said bolster, the said bearing comprising an 30 upper bearing portion and a lower abut-

ment portion; a footstep arranged in the lower portion of the bolster and comprising a ring having a central perforation for a spindle and a circular recess in its under side, and a disc arranged in the said recess; a 45 spring within the bolster and compressed between the abutment of the upper bearing and the ring of the footstep bearing; and a spindle mounted in the said upper and footstep bearings.

7. In a continuous spinning and doubling machine the combination of a lifting rail; a bolster mounted upon the said rail; a plain bearing comprising an upper bearing portion, a lower abutment portion, and an intermediate supporting portion forming a downward continuation of a segment of the upper bearing portion the said plain bearing being adapted to engage within the upper portion of the bolster, the wall of the latter and a coincident portion of the bearing opposite the intermediate supporting portion thereof being cut away to expose the spindle; means for applying drag to the exposed portion of the spindle; a footstep bearing arranged in the lower portion of the bolster and comprising a ring having a central perforation for a spindle and a circular recess in its under side, and a disc arranged in the said recess; a spring situated 60 within the bolster between the abutment of the upper bearing and the ring of the footstep bearing and adapted to press resiliently upon the latter; and a spindle mounted in the said upper and footstep bearings.

Signed at Manchester in the county of Lancaster, England, this 25th day of August A. D. 1921.

JOSEPH SHAW GAUNT.
HARRY DYSON.
